WINDOW GUARD

Joseph Kaufman, New York, N. Y.

Application July 8, 1937, Serial No. 152,505

15 Claims. (Cl. 20—71)

This invention relates to window guards.

An object of this invention is to provide an extensible window guard which may be adjusted to fit a relatively large range of window widths, and locked in adjusted position.

5 A further object of this invention is to provide a strong and rugged jimmyproof window guard of the character described, which shall be relatively inexpensive to manufacture, light in weight, easy to manipulate and withal, practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

20 In the accompanying drawings, in which are shown one of the various possible illustrative embodiments of this invention.

Fig. 1 is a front elevational view of a window guard embodying the invention, within a window frame;

Fig. 2 is a cross-sectional view taken on line 2—2 of Fig. 1;

Fig. 3 is an enlarged cross-sectional view taken on line 3—3 of Fig. 1;

30 Fig. 4 is a cross-sectional view taken on line 4—4 of Fig. 3;

Fig. 5 is a cross-sectional view taken on line 5—5 of Fig. 1;

Fig. 6 is an enlarged cross-sectional view similar to Fig. 4, but showing the guard in unlocked position;

Fig. 7 is a cross-sectional view taken on line 7—7 of Fig. 6;

Fig. 8 is a cross-sectional view taken on line 8—8 of Fig. 6;

Fig. 9 is a cross-sectional view taken on line 9—9 of Fig. 6; and

Fig. 10 is a cross-sectional view taken on line 10—10 of Fig. 6.

45 Referring now in detail to the drawings, 10 designates a window frame having side portions 11 formed with pairs of grooves 12 and 13 in which are slidably mounted the window sashes 14 and 15 respectively. Within the grooves 13, 50 between the furring strips 16 and below the sash 15 is a window guard 17 embodying the invention.

The window guard 17 is extensible, and comprised generally of a pair of slidably connected members 18 and 19, mechanism 20 to fix said

members against relative movement and key actuated, releasable locking means 21 to retain said mechanism in fixed position.

Member 18 comprises a pair of vertical flat bars 23, 24 resting on the bottom portion 10a of frame 10. Bar 23 is disposed in groove 13 at one side of the window frame. Said bar 23 is of such height as to substantially reach the underside of upper sash 15. Fixed to and between said bars 23, 24 are a plurality of spaced, parallel, 10 horizontal, similar grates 25 of channel shaped transverse cross section. The grates 25 have downwardly extending side flanges 26, the ends whereof pass through openings in bars 23, 24 and are headed, as at 27, to rivet said grates to 15 said bars. Bar 24 is formed with rectangular openings 28 just below each grate 25, for the purpose hereinafter appearing. Bar 24 may be shorter than bar 23, as shown in the drawings. Although six grates 25 are shown in the drawings, 20 it will be understood that any suitable number of grates may be employed.

Member 19 comprises a pair of vertical flat bars 30 and 31 interconnected by parallel, horizontal spaced grates 32 of channel shaped transverse cross section. The bar 30 is similar to bar 23 and is received in groove 13 at the other frame portion 11 and between the furring strips 16. Bar 31 does not extend to the bottom 10a of the frame, as illustrated in Fig. 1 of the drawings. There are as many grates 32 as grates 25, the former passing through openings 28 in bar 24. Bar 31 is formed with a rectangular opening 34 above each grate 32, through which passes one of the grates 25.

35 It will now be understood that the members 18, 19 are relatively movable, one guiding the other, to extend or shorten the width of the window guard to fit various sized windows.

A pair of said grates 32 (second and fifth from top and designated by numeral 32a) are formed with a plurality of closely spaced aligned openings 40 in the top walls of said grates. The length of grates formed with said openings determines the amount of adjustment that can be 45 made. For example, if there are twelve inches of openings 40, the window guard can be widened twelve inches.

The mechanism 20 for retaining the members 18 and 19 in relatively fixed position comprises 50 a pair of parallel, elongated, similar, symmetrically disposed channel shaped members 42 having inwardly extending flanges 43. The members 42 are spaced apart and disposed at opposite sides of the grates 32, 32a, and adjacent the 55

bar 24. The channel shaped members 42 are fixed to one another by rivets 46 and 47, carrying spacing sleeves 46a and 47a disposed between said members. The rivet 46 is located above the 5 third grate 32, whereas, the rivet 47 is located below the fourth grate 32a. As will appear hereinafter, said rivets limit reciprocation of the mechanism 20. When mechanism 20 is moved upwardly, the sleeve 47a on rivet 47 will contact the under edges of one grate 32 to limit upward movement, and when said mechanism is moved downwardly, the spacing sleeve 46a, on the rivet 46, will contact another grate 32 to limit downward movement.

15 The mechanism 20 is connected to the bar 24 for sliding movement thereon, by means of a pair of spaced, vertical plates 48, fixed to the bar 24 in spaced relation thereto, by rivets 49. The plates 48 are substantially square in shape 20 and disposed between the channel shaped members 42, and engage the inner surfaces of adjacent flanges 43, of the channel shaped members 42.

Fixed to and between the members 42, are a 25 pair of spaced, horizontal plates 52, each carrying an upwardly extending pointed element or pin 53 adapted to be received within the openings 40 in the grates 32a. The plates 52 are disposed below the grates 32a. When the mechanism 20 is in releasing position, as shown in Fig. 6 of the drawings, the pointed elements 53 are disposed below the grates 32a. In such position, the members 18 and 19 may be slidably moved one relative to the other to widen or 35 narrow the window guard. Upon moving the mechanism 20 upwardly however, the elements 53 engage within aligned openings 49 to prevent such relative movement between the members 18 and 19.

40 The locking means 21 for holding the mechanism 20 in its "up" position, as shown in Fig. 3 of the drawings, comprises a channel shaped member 60 having parallel flanges 61, adapted to receive a portion of the mechanism 20 therebetween, and formed with extending apertured ears 62, receiving the ends of a transverse, horizontal pivot pin 64, which serves to pivotally attach said member 60 to said mechanism. The lower end of member 60 is formed with a slot 50 or notch 65, and riveted to the inner surface of said member, transverse of said slot, is a strip 66 carrying a roller 67. The pivot pin 64 is so located, and the member 60 is of such length, that when the mechanism 20 is in "down" or 55 releasing position, the roller 67 will contact one of the grates 32, to maintain said member in inclined position, with the lower end of said member spaced from said mechanism; and when said mechanism is "up" or locking position, said member will be in vertical position with the roller still in engagement with said grate.

On member 60 is a key cylinder 68, carrying a latch 69, disposed between the flanges 61. The latch 69 is narrower than the space between 65 the inner edges of the flanges 43, whereby said latch may move through said space when mechanism 20 is moved upwardly. When said mechanism 20 is in its "up" position, turning of the cylinder 68 by a key, through an angle of 90°, 70 will cause the latch to engage the flanges 43 of the channel shaped members 42 to lock the member 60 in vertical position, as shown in Figs. 3 and 4 of the drawings.

It will now be understood that to lock the 75 window guard, it is merely necessary to raise

the mechanism 20 causing the locking means 21 to swing to vertical position, and the elements 53 to engage within a pair of aligned openings 40. The roller 67 serves to prevent rubbing off of the paint on the portion of the grate 32 it 5 contacts.

The lower rivet 47 aids in rendering the window guard jimmyproof. When the member 21 is swung to vertical position, the key is inserted into the cylinder 68 and given a quarter of a 10 turn to bring the latch 69 in engagement with the flanges 43. The key may then be removed and the window guard is then locked in place on the window within the grooves 13 of the window frame, and cannot be removed. 15

When it is desired to remove the window guard from the window frame, the key is again inserted in the cylinder 68 and given a quarter of a turn in the opposite direction to bring the latch 69 to vertical position. The member 21 20 may then be swung outwardly, to the position shown in Fig. 6, the mechanism 20 being lowered to disengage the pointed elements 53 from openings 40. The members 18 and 19 may then be moved together, and the window guard 25 removed from the window frame. Although the window guard is shown in the drawings to have six grates, two of which are formed with openings to receive two pointed elements, it will be understood that the number of grates, the number 30 of grates with the openings, and the number of pointed elements may be varied to suit.

When the window guard is used with casement windows, the bars 23 and 30 may be provided with outwardly extending pins and the window 35 frame formed with sockets to receive said pins.

It will thus be seen that there is provided a 40 device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying 45 drawings is to be interpreted as illustrative and not in a limiting sense.

Having thus described my invention, I claim as new and desire to secure by Letters Patent:

1. A window guard comprising a pair of extensible members, one of said members having a vertical bar, and the other of said members having a plurality of spaced horizontal grates connected to said vertical bar for sliding movement at right angles thereto, an elongated member connected to said bar for sliding movement longitudinally of said bar, means on said elongated member for engaging said grates in one longitudinal position of said member to prevent sliding movement of said grates relative to said vertical bar, and means for locking said elongated member in said position against sliding movement relative to said bar. 50

2. A window guard comprising a pair of extensible members, one of said members having a vertical bar, and the other of said members having a plurality of spaced horizontal grates, an elongated member slidably mounted on said bar, means on said elongated member for engaging said grates, and means for locking said elongated member in engaging position, said last means comprising a member pivoted to said elongated member and engaging one of said grates, and means for fixing said pivoted member to said elongated member against pivotal movement. 55

3. A window guard comprising a pair of extensible parts, each part comprising a pair of vertical bars interconnected by a plurality of parallel grates, one of the vertical bars of each part being formed with openings to slidably receive the grates of the other part, an elongated member connected to a bar of one of said parts for longitudinal sliding movement relative thereto, a plurality of grates of the other part being formed with a plurality of openings, and means on said slidably mounted member to engage within said last mentioned openings in one longitudinal position of said elongated member to lock the grates of the other part against sliding movement, and means for locking said elongated member in said position against longitudinal sliding movement.
4. A window guard comprising a pair of slidably connected extensible parts, one part comprising a vertical bar formed with a plurality of openings, the other part comprising a plurality of horizontal grates passing through said openings, said grates being formed with a plurality of aligned openings, a pair of elongated vertical channel shaped members disposed on opposite sides of said grates, means for fixing said channel shaped members one to the other, means fixed to said bar and slidably engaging a pair of flanges on said channel shaped members to slidably connect the latter to said bar, and a pair of pointed elements on said channel shaped members adapted to be received within the openings in said grates.
5. A window guard comprising a pair of extensible slidably connected parts, one part comprising a vertical bar, the other part comprising a plurality of horizontal grates, an elongated member slidably connected to said vertical bar and disposed longitudinally thereof, means on said elongated member adapted to lockingly engage said grates, a member pivoted to said elongated member, a key actuated latch on said pivoted member, said pivoted member being in engagement with one of said grates, said latch being adapted to engage said elongated member to hold the pivoted member against pivotal movement.
6. A window guard comprising a pair of extensible slidably connected parts, one including a vertical bar and formed with a plurality of spaced openings, the other part including a plurality of parallel, horizontal grates extending through said openings, and means interconnecting said parallel grates; a pair of vertical plates fixed to said vertical bar and spaced therefrom, a pair of elongated, vertical, parallel, interconnected channel shaped members symmetrically disposed to one another and on opposite sides of said grates having aligned flanges substantially in contact with said bar and in engagement with said plates, whereby said channel shaped members may reciprocate relative to said vertical bar, and means to limit reciprocation of said channel shaped members in opposite directions, a pair of said grates being formed with a series of aligned openings, a pair of pointed elements fixed to and between said channel shaped members and adapted to engage within the openings in said grates, a member pivoted to said channel shaped members, a key cylinder on said pivoted member, a latch controlled by said key cylinder and adapted to engage a pair of flanges on said channel shaped members, and a roller on said pivoted member in engagement with one of said grates.
7. A window guard comprising a pair of extensible slidably connected parts, one including a vertical bar and formed with a plurality of spaced openings, the other part including a plurality of parallel, horizontal grates extending through said openings, and means interconnecting said parallel
- grates; a pair of vertical plates fixed to said vertical bar and spaced therefrom, a pair of elongated, vertical, parallel, interconnected channel shaped members symmetrically disposed to one another and on opposite sides of said grates having aligned flanges substantially in contact with said bar and in engagement with said plates, whereby said channel shaped members may reciprocate relative to said vertical bar, and means to limit reciprocation of said channel shaped members in opposite directions, a pair of said grates being formed with a series of aligned openings, a pair of pointed elements fixed to and between said channel shaped members and adapted to engage within the openings in said grates, a member pivoted to said channel shaped members, a key cylinder on said pivoted member, a latch controlled by said key cylinder and adapted to engage a pair of flanges on said channel shaped members, and a roller on said pivoted member in engagement with one of said grates.
8. A window guard comprising a pair of extensible slidably connected parts, one including a vertical bar and formed with a plurality of spaced openings, the other part including a plurality of parallel, horizontal grates extending through said openings, and means interconnecting said parallel grates; a pair of vertical plates fixed to said vertical bar and spaced therefrom, a pair of elongated, vertical, parallel, interconnected channel shaped members symmetrically disposed to one another and on opposite sides of said grates having aligned flanges substantially in contact with said bar and in engagement with said plates, whereby said channel shaped members may reciprocate relative to said vertical bar, and means to limit reciprocation of said channel shaped members in opposite directions, a pair of said grates being formed with a series of aligned openings, a pair of pointed elements fixed to and between said channel shaped members and adapted to engage within the openings in said grates, a member pivoted to said channel shaped members, a key cylinder on said pivoted member, a latch controlled by said key cylinder and adapted to engage a pair of flanges on said channel shaped members, and a roller on said pivoted member in engagement with one of said grates.
9. A window guard comprising a pair of slidably connected extensible members, one of said members having a vertical bar and the other of said members having a horizontal bar formed with a plurality of spaced openings and being slidably connected to said vertical bar for movement at right angles thereto, and a member lying alongside of said vertical bar and being connected thereto for sliding movement longitudinally thereof, means on said last member adapted to selectively engage within said openings when moved longitudinally of said vertical bar in one direction and to disengage from said openings when moved in an opposite direction, and means for locking said last mentioned member against longitudinal movement relative to said vertical bar in engaging position.
10. A window guard comprising a pair of extensible members, one of said members comprising a bar, the other of said members comprising a pair of bars slidably connected to said first bar for movement at right angles thereto, one of said pair of bars being formed with a plurality of spaced openings, a member lying alongside said first bar and being connected thereto for longitudinal sliding movement, a pin on said last member adapted to selectively engage within said openings when said member is moved longitudinally of said first bar in one direction and to disengage

- from said openings when moved in an opposite direction, a member pivoted at one end thereof to said last member, the other end of said pivoted member being adapted to engage said other 5 of said pair of bars when said pin is in engaging position within one of said openings, to prevent longitudinal movement of said elongated member, said pivoted member being adapted to be pivotally moved about the first end thereof to permit 10 longitudinal movement of said elongated member and disengagement of said pin from said opening, and means for locking said pivoted member alongside said elongated member against pivotal movement to prevent longitudinal movement of 15 said elongated member in said opposite direction whereby to lock said pair of bars to said first bar against relative movement.
11. A window guard comprising a pair of slidably connected extensible parts, one part comprising a vertical bar, the other part comprising a plurality of horizontal grates slidably connected to said bar, one of said grates being formed with a plurality of spaced openings, a pair of elongated vertical members disposed on opposite sides 20 of said grates and alongside said vertical bar, means for fixing said elongated members to one another, means on said vertical bar slidably connecting said elongated members to said vertical bar, means fixed to said elongated members and 25 disposed therebetween adapted to be selectively engaged within said openings upon slidably moving said elongated members longitudinally of said vertical bar.
12. A window guard comprising a pair of slidably connected extensible parts, one part comprising a vertical bar, the other part comprising a plurality of horizontal grates slidably connected to said bar, one of said grates being formed with a plurality of spaced openings, a pair of elongated vertical members disposed on opposite sides 30 of said grates and alongside said vertical bar, means for fixing said elongated members to one another, means on said vertical bar slidably connecting said elongated members to said vertical bar, means fixed to said elongated members and 35 disposed therebetween adapted to be selectively engaged within said openings upon slidably moving said elongated members longitudinally of said vertical bar, a member of channel-shaped transverse cross-section pivoted at one end to said 40 elongated members and having flanges receiving said elongated members therebetween when said pivoted member is moved against said members, the opposite end of said pivoted member being adapted to engage one of said grates to retain 45 said engaging means within one of said openings when lying against said elongated members.
13. A window guard comprising a pair of slidably connected extensible parts, one part comprising a vertical bar, the other part comprising a plurality of horizontal grates slidably connected to said bar, one of said grates being formed with a plurality of spaced openings, a pair of elongated vertical members disposed on opposite sides of 50 said grates and alongside said vertical bar, means for fixing said elongated members to one another, means on said vertical bar slidably connecting 55
- said elongated members to said vertical bar, means fixed to said elongated members and disposed therebetween adapted to be selectively engaged within said openings upon slidably moving said elongated members longitudinally of said vertical bar, a member of channel-shaped transverse cross-section pivoted at one end to said elongated members and having flanges receiving said elongated members therebetween when said pivoted member is moved against said members, the opposite end of said pivoted member being adapted to engage one of said grates to retain 60 said engaging means within one of said openings when lying against said elongated members.
14. An extensible window guard comprising a pair of slidably connected parts, one part having a vertical bar, the other part having a plurality of horizontal grates fixed to move together and 65 slidably connected to said bar, a pair of elongated vertical members disposed on opposite sides of said grates and alongside of said vertical bar and lengthwise thereof, means for fixing said elongated members to one another, means for connecting said elongated members to said vertical bar for sliding movement lengthwise thereof, co-operating means on said elongated members and on one of said grates for retaining the latter in various adjusted positions relative to said vertical bar upon moving said vertical members lengthwise of said vertical bar in one direction, and means for locking said elongated members in 70 retaining position.
15. An extensible window guard comprising a pair of slidably connected parts, one part having a vertical bar, the other part having a plurality of horizontal grates fixed to move together and 75 slidably connected to said bar, a pair of elongated vertical members disposed on opposite sides of said grates and alongside of said vertical bar and lengthwise thereof, means for fixing said elongated members to one another, means for connecting said elongated members to said vertical bar for sliding movement lengthwise thereof, co-operating means on said elongated members and on one of said grates for retaining said grate in various adjusted positions relative to said vertical bar upon moving said vertical members lengthwise of said vertical bar in one direction, and means for locking said elongated members in 80 retaining position, said means comprising a member pivoted to said elongated members and adapted to engage another of said grates when said elongated members are in grate retaining position and said pivoted member is swung against said elongated members, and key actuated means for locking said pivoted member to said elongated members.

JOSEPH KAUFMAN.
